(57) **CLAIM**

An ornamental design for a hard protective helmet cap with ventilation to assist with cooling the wearer, as shown and described.

DESCRIPTION

FIG. 1 is a right side view of a hard protective helmet cap with ventilation to assist with cooling the wearer showing my new design;

FIG. 2 is a front view thereof;

FIG. 3 is a back view thereof;

FIG. 4 is a bottom view thereof; and,

FIG. 5 is a top view thereof.

The details shown in broken lines in FIGS. 1-4 are for illustrative purposes only and form not part of the claimed design.
